UNITED STATES PATENT OFFICE.

JOHANN KLEIN, OF FRANKENTHAL, BAVARIA, GERMANY.

FILTER.

SPECIFICATION forming part of Letters Patent No. 367,212, dated July 26, 1887.

Application filed March 7, 1887. Serial No. 230,030. (No model.)

To all whom it may concern:

Be it known that I, JOHANN KLEIN, a subject of the King of Bavaria, residing at Frankenthal, in the Kingdom of Bavaria, Germany, have invented certain new and useful Improvements in Filters; and I hereby declare that the following is a full, clear, and exact description of the invention, which will enable others skilled in the art to which it appertains to make and use the same, reference being had to the accompanying drawings, which form a part of this specification, and in which—

Figure 1 is a vertical sectional view of my improved filtering apparatus. Fig. 2 is a horizontal sectional view on line xx , Fig. 1. Fig. 3 is a vertical sectional view of a portion of the apparatus, showing the communicating pipe. Fig. 4 is a vertical sectional detail view showing the means for securing the separating-grate. Fig. 5 is a horizontal sectional view of the same; and Fig. 6 is a vertical sectional view taken on the line xx of Fig. 2.

Similar letters of reference indicate corresponding parts in all the figures.

My invention has relation to filters having a number of inlets and outlets in the sides, and having a number of filtering-sections alternating with open spaces; and it consists in the improved construction and combination of parts of such a filter, as hereinafter more fully described and claimed.

In the accompanying drawings, the letter M indicates a smooth metallic cylinder, having its bottom plate, A, provided with suitable axles for wheels C, and having a removable top or cover, D, secured air-tight to the cylinder by means of bolts D', the lower ends of which may be secured to the bottom plate, and hand-wheels E and packing ring or gasket F.

Flanged rings G are secured at intervals upon the outside of the cylindrical casing, and the branches e and e' of the feed-pipe or inlet-pipe H open, respectively, at the bottom of the cylinder and in one of the rings, and the branches a and a' of the outlet-pipes I open, respectively, in one of the rings and at the top of the cylinder, the cylinder having in this case two of these rings.

A perforated plate, p, having feet J, is placed at the bottom of the cylinder, and a suitable filtering-cloth is placed upon this plate, whereupon a layer, K, of some suitable filtering ma-

terial, is placed upon the cloth and is covered with another cloth or felt, L, upon which another plate, p, without feet is placed. A second set of perforated plates and filtering material is supported by the feet of the lower plate above this set, forming a space, N, between them, and a grate or circular frame, q, having radiating ribs, is placed upon the top of this set for the purpose of supporting the weight of the layers of filtering material above them. The rim of this circular frame is formed with perforations P at intervals, and bolts B, having handles at their inner ends, fit 65 and slide in these perforations, having grooves y in their under sides, into which the ends, of screws x project, the said screws and grooves guiding the bolts and limiting their play. The outer ends of these radiating bolts fit into 70 sockets s in the flanged rings, having screw-caps Q in their ends, and the bolts serve to support the circular frames, of which there are two shown in the apparatus illustrated in the drawings. Two sets of filtering-plates and 75 their interposed material are placed above the lower frame, whereupon another frame is placed upon the upper set, and still two more sets of plates and filtering layers are placed above this frame. It will now be seen that as 80 the fluid to be filtered is let in through the inlet-pipes it will pass into the spaces between the filtering sets, being thus distributed to the entire area of the filtering element, and the fluid may pass upward or downward and may 85 after passing through two filtering elements pass out through the outlet-pipes.

Any gas or compressed air contained in the fluid may pass freely up through the filtering elements, and it is therefore only necessary to 90 have air-escape valves R at the upper ends of the inlet and outlet pipes.

For the purpose of insuring the more perfect escape of air or gases, and also for the purpose of expediting the final emptying of the 95 fluid in the filter, I attach a vertical pipe, b, to the side of the cylinder, the said pipe having perforations c at each space between the filtering elements, so that air or gas as well as fluids may pass from the spaces into the pipe, 100 and the upper end of the pipe is open, so that air or gas may escape into the top of the cylinder and escape through an outlet-cock, S, in the top.

As the pipe would be liable to receive unfiltered fluid through the perforated portions and carry it to a space or compartment having filtered fluid, the pipe is provided with a rod 5 or core, *w*, having a groove, *d*, in one side, which may register with the perforated portions of the pipe, and the lower end of this core passes out through a stuffing-box, *v*, in the bottom of the cylinder, and is provided 15 to with an upwardly-curved handle, *h*, by means of which it may be turned.

A flange, *o*, projects from the bottom of the cylinder, and may be provided with marks *z*, indicating the open and closed position of the 20 handle and of the core, the flange projecting over and protecting the handle. It will thus be seen that by turning the handle and the core the perforated portions of the vertical pipe may be opened or closed, allowing the air and gas or the fluid to pass into the pipe, or preventing the fluid from passing from a compartment containing impure fluid to a compartment containing pure and filtered fluid.

It will also be seen that as the fluid passes 25 in one direction from the lower branch of the inlet pipe and in two directions from the other the filtering may be performed rapidly and perfectly, and by having all the perforated plates and the filtering material loosely supported in the cylinder all these parts may 30 readily be removed from the cylinder for the purpose of renewing them or cleaning them and for the purpose of cleaning the cylinder.

Having thus described my invention, I claim 35 and desire to secure by Letters Patent of the United States—

1. In a filter, the combination of a cylinder having flanged rings at equal distances formed with alternating inlets and outlets, and having 40 radiating sockets provided with removable screw-caps, filtering elements in the cylin-

der alternating with spaces, circular frames placed in every other space and formed with radiating perforations registering with the 45 sockets in the cylinder, bolts in the perforations, having handles at their inner ends and having longitudinal grooves in their undersides, and screws in the perforations, having their ends in the grooves of the bolts limiting their stroke and guiding them, as and for the 50 purpose shown and set forth.

2. In a filter, the combination of a cylinder having alternating filtering elements and spaces, and having alternating inlets and outlets in every other space, a vertical pipe having 55 perforated portions at every space, secured at the side of the cylinder, and a core having a longitudinal groove registering with the perforated portions in the pipe, and provided with a handle for turning it, as and for the purpose shown and set forth.

3. In a filter, the combination of a cylinder having alternating filtering elements and spaces, a vertical pipe secured to the side of the cylinder, and having perforated portions 65 registering with the spaces, a core or rod within the pipe, having a longitudinal groove corresponding to the perforated portions of the pipe and passing out through a stuffing-box in the bottom of the cylinder, an upwardly-curved handle, and a semicircular shield or flange at the bottom of the cylinder over the handle, having marks for the two positions of the handle, as and for the purpose shown and set forth. 75

In testimony that I claim the above as my own invention I hereto have affixed my signature in the presence of two witnesses.

JOHANN KLEIN.
